US0D1112175S

(12) **United States Design Patent** (10) Patent No.: **US D1,112,175 S**
(45) Date of Patent: ** Feb. 10, 2026

(54) **WIRELESS CONNECTIVITY DEVICE**

(71) Applicant: **Amazon Technologies, Inc.**, Seattle, WA (US)

(72) Inventors: **Jeremy Paul Wolf**, San Francisco, CA (US); **Fred Bould**, Menlo Park, CA (US); **Martin Duhayon**, San Francisco, CA (US); **Jamie Starr Perin**, San Francisco, CA (US)

(73) Assignee: **Amazon Technologies, Inc.**, Seattle, WA (US)

(**) Term: **15 Years**

(21) Appl. No.: **29/940,664**

(22) Filed: **May 3, 2024**

Related U.S. Application Data

(63) Continuation of application No. 29/865,589, filed on Aug. 2, 2022, now Pat. No. Des. 1,030,727.

CLAIM

The ornamental design for a wireless connectivity device, as shown and described.

DESCRIPTION

FIG. 1 is a front, bottom, right-side perspective view of a wireless connectivity device;

FIG. 2 is a back, top, left-side perspective view thereof;

FIG. 3 is a bottom view thereof;

FIG. 4 is a top view thereof;

FIG. 5 is a left-side view thereof;

FIG. 6 is a right-side view thereof;

FIG. 7 is a front view thereof; and,

FIG. 8 is a back view thereof.

The dashed broken lines depict portions of the wireless connectivity device that form no part of the claimed design.

1 Claim, 8 Drawing Sheets
